Letters Patent No 1894 Dated Feb 3rd 1864.

Design for the Plates of a Stove.

The schedule referred to in these Letters Patent and making part of the same.

To all whom it may concern:

Be it known that I, Nicholas S. Vodder, of the City of Troy in the County of Rensselaer, and State of New York, have invented or produced a new and original ornamental Design for Plates of a Stove, and I do hereby declare that the following is a full and exact description thereof, reference being had to the annexed photographs, in which-

Fig. 1. represents the top, and

Fig. 2. the base of a stove having my said ornamental design.

This ornamental design consists of a series of plates a, scallops b, rosettes c, and standards d, with arched tops and pendants e, on a top plate. F: a series of beads g, rosettes h, and standards i, arched together at top, on an upper base plate. J: two series of scallops k, k, and a chain of wreaths l, in a panel, m, on an upright base plate n, and a series of scallops o, in the border of a base plate bottom p, the said ornaments being shaped and arranged upon the said plates, and the latter formed, so as to present the appearance represented by the aforesaid photographs.

What I claim as new and of my invention or production, and desire to secure by Letters Patent is

The above described ornamental design of the plates F, J, N, and P, of a stove.
